DISPENSER FOR SHEETS

Frank L. Broeren, Neenah, and Archie S. Krueger, Green Bay, Wis., assignors to Marathon Paper Mills Company, Rothschild, Wis., a corporation of Wisconsin

Application February 18, 1938, Serial No. 191,344

10 Claims. (Cl. 312—62)

This invention relates to a dispenser adapted particularly for use in the dispensing of interleaved folded waxed sheets which by reason of their smooth surface must be firmly and evenly retained in stacked formation during the dispensing operations, since they do not tend to frictionally adhere to one another but develop a tendency to slip or slide, which must be overcome in order to prevent displacement.

10 The mechanism of the present invention therefore makes provision for the confinement and retention of the stacked sheets during all stages in the dispensing operation, and also makes provision for feeding the stack of sheets toward the dispensing opening and properly positioning the sheets until the last sheet has been withdrawn.

15 Further objects and details of the invention will appear from the description thereof in conjunction with the accompanying drawings, 20 wherein

25 Figure 1 is a perspective view of a dispenser embodying the features of the present invention,

Figure 2 is a fragmental side view of the dispenser with the cover opened,

30 Figure 3 is a sectional view taken on lines 3—3 of Figure 1.

Figure 4 is a perspective view of the dispenser in opened position,

35 Figure 5 is a perspective fragmental detail view of the latch mechanism,

Figure 6 is a fragmental plan view of the dispenser showing the cover in partially opened position,

40 Figure 7 is a sectional view taken on lines 7—7 of Figure 3,

Figure 8 is a sectional view similar to Figure 7 of a modified form of the dispenser, and

45 Figure 9 is a fragmental detail perspective view of the link bar hinge connection.

40 Referring to the drawings, the dispenser comprises a metal container 1 having a cover 2 hinged to the upper edge of the side walls 14 by means of pintles 27. The cover 2 is provided with legs or extensions 26 which are positioned

45 inside the container adjacent the side walls 14, as shown in Figures 1 and 2, for hinging the cover on the pintles 27. The legs 26 are provided with cut out portions 3 which permit the cover to be swung open to the position as shown in Figure

50 4, the cut out portions 3 serving as a stop to limit the outward swing of the cover 2.

55 The container 1 comprises a bottom 17, side walls 14, rear wall 21, and front wall 13 preferably formed from a single metal blank suitably stamped and shaped to form the container as

illustrated in Figures 1 and 4. The rear wall is provided with side flanges 33 overlapping the side walls 14 and an upper flange portion 30 having a supporting ledge 31 for engaging and supporting the edge 11a of the cover 2 in closed position as shown in Figure 3. The rear wall may be provided with suitably shaped openings 4 for suspending the receptacle on brackets if desired.

The upper portions of side flanges 33 are provided with integral supporting wings 25, substantially triangular in shape as shown in Figures 2 and 3. The supporting wings are inclined slightly inwardly of the receptacle. The portions 25a of the supporting wings serve to support the edges of the cover 2 in closed position.

Side walls 14 of the receptacle extend substantially to the horizontal medial portion of the rear wall 21 as shown in Figure 4. The front upper edge portion of the side wall adjacent the front wall is cut out at 28 in the form of a quarter circle as shown in Figure 2 which mates with a cut out quarter circle portion 38 provided in the side wall 16 of hinged cover 2 thereby forming an opening at the side walls of the dispenser for exposing the edge portions of the sheets within the dispenser as shown in Figure 1.

Side walls 14 are cut along lines 32a to permit insertion of portions 32 integral with the ends of front wall 13. The upper edge of the front wall 13 is bent outwardly to provide a lip portion 23 as shown in Figure 3 for supporting the free portions of the sheet A protruding through the dispensing slot.

The bottom 17 of the receptacle is provided with spaced ribs 18 as shown in Figure 7 which serve to support the stack of sheets A in spaced elevated relation above the bottom 17 as well as to guide the follower plate 40.

The hinged cover 2 comprises a wall 11 which forms the top of the dispenser, side walls 16, and a front wall 10. The lower edge of front wall 10 is bent outwardly to provide a lip 22 as shown in Figure 3 spaced from the lower lip 23 of the receptacle thereby forming a slot for dispensing the sheets from the dispenser. Side walls 16 are provided with legs 26 as previously described for hinging the cover on pintles 27. Legs 26 are offset from the side walls 16 to provide an offset portion 34 as shown in Figure 4 which abuts the upper edges 35 of the side walls 14 of the receptacle when the cover is in closed position.

Side walls 16 are cut along lines 37 to permit insertion of the portions 35 which are integral with the ends of the front wall 10. This con-

struction permits wall 10 to incline rearwardly as shown in Figure 3.

In order to releasably lock the hinged cover 2 a pivoted plate member 80 is provided on the rear wall 21 of the dispenser. For suitably supporting the pivoted plate there is provided a plate 80a which is fixedly welded to the wall 21 of the container as shown in Figure 4. The plate 80a carries a pin 84 on which is pivoted the plate member 80. The pivoted plate member is made from an integral metal plate shaped to provide a latch handle 81 for manually oscillating the plate on its pivot, an upper tongue portion 82, a lower tongue portion 83, and a foot portion 86. The pivoted plate member is positioned on pin 84 so as to permit latch handle 81 to extend through the opening 90 provided in the flange portion 30 as shown in Figure 5. The opening 90 is elongated in shape having rounded ends 91 and 92 which serve to limit the movement of latch handle 81 in both directions. As shown in Figure 4, the pivoted member 80 is eccentrically pivoted on pin 84 adjacent one end so that the weight of the member due to its elongated shape including the leg portion 86, tends to move the member normally to the position shown in Figures 4 and 5 until latch handle 81 abuts the end 92 of the slot 90.

When the cover 2 is moved into closed position 30 a lug 70 provided inside the top wall 11 contacts the curved portion 82a of the upper tongue 82, thereby moving the tongue 82 to the left of the position shown in Figure 5, until lug 70 moves past the tip of the tongue. At this point the weight of pivoted plate 80 will cause it to return to its initial position so that tongue 82 will interlock with lug 70 thereby locking the hinged cover 2. When it is desired to open cover 2 the latch handle 81 is moved to the left from the position shown in Figure 1, thereby releasing lug 70 from tongue 82 so as to permit the cover 2 to be swung open.

In order to position the stack of sheets within the dispenser in proper relation to the dispensing slot a follower plate 40 is provided which is urged toward the dispensing slot by spaced upper and lower link bars 45 one end of each bar being pivoted to the rear wall 21 of the dispenser. For retaining the rear end of link bars 45, plates 60 are affixed to the rear wall 21 by rivets 61 as shown in Figure 9. Plates 60 are provided with perforated ears 65 and 66 adapted to engage flanges 53 and 54 provided on links 45 which are retained in position by a cotter pin 67. A coil spring 64 is provided on the shank of cotter pin 67 having one end 63 retained by portion 62 integral with plate 60 and the other end 70 bearing against link 45. Portions 68 at the end of link bars 45 are bent back to provide space for springs 64. Springs 64 urge link bars 45 toward the dispensing opening. The other end of each link 45 is provided with a slot 44 adapted to slidably receive lugs 41 and 42 integral with follower plate 40 from which they are punched out. The outer ends of the link bars are curved in order to reduce their friction against the pusher plate 40. As shown in Figures 2, 4, and 7, the lower end portion 47 of the link bars is slightly offset from the body of link bar 45 so that only the end portion 47 contacts the follower plate 40 when lugs 41 and 42 are positioned at the outer end of the slots 44 as shown in Figures 2 and 7. In this position the end portion 46 of the link bar 45 does not contact the follower plate 40.

A U-shaped retaining member 43 is welded to the medial portion of follower plate 40 as shown in Figure 3. Member 43 serves to retain the follower plate 40 in its rearmost position in the dispenser when it is desired to refill the dispenser with a new stack of sheets. When the follower plate is manually moved toward the rear wall 21, the member 43 contacts the lower hook 83 on pivoted plate 80, thereby swinging pivoted plate member 80 to the right. When the tip of the hook 83 slides past the edge of member 43 it swings back in locking position as shown in Figure 5 thereby retaining the follower plate adjacent the rear wall 21.

After the stack of sheets is placed within the receptacle 1, the hinged cover is swung into closed position. Lug 70 on the inside of the top 11 will then contact upper hook 82 causing plate 80 to swing to the left of the position shown in Figure 5 and in the direction as indicated by dotted arrow in Figure 6. Hook 83 will then be automatically released from the U-shaped member 43 thereby allowing the follower plate to urge forwardly the stack of sheets toward the dispensing opening. At the same time hook 82 will move 25 into engagement with lug 70 thereby locking the hinged cover in closed position.

The follower plate 40 is preferably V-shaped in cross-section as shown in Figure 3 so as to have a contour substantially complementary to the combined sectional contour of the front panels 10 and 13, these panels being inclined inwardly toward the rear wall as shown in Figure 3. Follower plate 40 is provided with an upper flange 50 for retaining the upper edge of the stack of 35 sheets in the dispenser. Follower plate 40 is also provided with a lower foot portion 51 which is positioned between the spaced ribs 18 as shown in Figure 7. Foot portion 51 serves to engage the lower edge portions of the sheets and prevents 40 the rearmost sheets from binding or slipping beneath the follower plate. As shown in Figure 7 the lower edges of the follower plate slide on the spaced ribs 18 on the bottom of the dispenser thereby minimizing frictional contact.

It is advantageous to construct the dispenser as previously described so that the rear wall 21 tilts slightly rearwardly past the vertical plane of the dispenser as shown in Figure 3. Top wall 11 is also displaced rearwardly as compared with the bottom wall 17, so as to throw the weight of the dispenser toward the rear wall. This construction is advantageous in overcoming tipping over of the dispenser when the sheets are removed through the dispensing opening, as the center of gravity of the dispenser is located closer to the rear wall 21 of the dispenser than to the front wall.

Figure 8 illustrates a modified form of the dispenser wherein the cross-sectional dimension of the dispenser is elongated compared with the sectional contour of the dispenser illustrated in Figure 1. In this construction the follower plate 40 is carried by a pair of upper and lower link bars 44 having a construction similar to the link bars shown in Figure 7. This construction serves to guide the follower plate 40 evenly and smoothly within the dispenser.

It is obvious that numerous changes and modifications may be made in the construction utilizing the essential principles of the invention which are intended to be included within the scope of the appended claims. Although the invention is primarily designed to meet the special requirements involved in the even and uniform

feeding of waxed paper sheets in interleaved relation to one another in a stack, nevertheless, the mechanism is well adapted to the feeding of sheets of ordinary unwaxed paper, which may 5 be used either as wrappers or as napkins, towels, toilet sheets or the like.

We claim:

1. A dispenser for folded sheets, comprising a container for receiving a stack of sheets, said 10 container comprising a bottom wall, side walls, a front wall and a rear wall, a cover hinged to said container, a lug member provided on said cover, said cover terminating short of the upper edge of the front wall when in closed position 15 thereby providing an elongated slot for withdrawal of the sheets, a follower plate hinged to the rear wall and adapted to bear against the stack of sheets for urging the stack toward said slot, said follower plate being provided with a 20 retaining member on its rear face, a gravity actuated plate member pivoted on the rear wall of the receptacle, said plate member being provided with a handle for manually oscillating same, a slot in said container for accommodating the 25 free end of said handle, an upper hook member on said plate member for engaging the lug member on said cover for releasably locking the cover in closed position, a lower hook portion integral with said plate member for engaging the retaining member on the rear face of the follower plate for retaining the same in retracted position, the lug on said cover contacting the 30 said upper hook portion for automatically releasing the follower plate upon closing the said cover. 35
2. A dispenser for folded sheets, comprising a container for receiving a stack of sheets, said container comprising a bottom wall, side walls, a front wall and a rear wall, a cover hinged to said container, a lug member provided on said cover, 40 said cover terminating short of the upper edge of the front wall when in closed position thereby providing an elongated slot for withdrawal of the sheets, a follower plate hinged to the rear wall and adapted to bear against the stack of sheets for urging the stack toward said slot, said follower plate being provided with a retaining member on its rear face, a gravity actuated plate member pivoted on 45 the rear wall of said receptacle, said plate member being provided with spaced upper and lower hook portions extending within the receptacle and a latch member extending upwardly through the said slot provided in the upper flange portion of the rear wall of the receptacle, said latch handle being manually actuated for releasing the hinged cover, said upper hook member being adapted for engaging the lug member on said cover for releasably locking the cover in closed 50 position, said lower hook portion being adapted for engaging the retaining member on the rear face of the follower plate for retaining the same in retracted position and for automatically releasing the follower plate upon closing the said cover. 55
3. A dispenser for folded sheets, comprising a container for receiving a stack of sheets, said container comprising a bottom wall, side walls, a front wall and a rear wall, a cover hinged to said container, a lug member provided on said cover, 60 said cover terminating short of the upper edge of the front wall when in closed position thereby providing an elongated slot for withdrawal of the sheets, a follower plate hinged to the rear wall adapted to bear against the stack of sheets 65
4. A dispenser for folded sheets, comprising a container for receiving a stack of sheets, said container comprising a bottom wall, side walls, a front wall and a rear wall, a flange portion provided at the upper portion of said rear wall, said flange portion being provided with a slot for receiving a latch handle and limiting the movement of same, a cover hinged to said container, a lug member provided on said cover, said cover terminating short of the upper edge of the front wall when in closed position thereby providing an elongated slot for withdrawal of the sheets, a follower 70 plate hinged to the rear wall and adapted to bear against the stack of sheets for urging the stack toward said slot, said follower plate being provided with a retaining member on its rear face, a gravity actuated plate member pivoted on the rear wall of said receptacle, said plate member being provided with spaced upper and lower hook portions extending within the receptacle and a latch member extending upwardly through the said slot provided in the upper flange portion of the rear wall of the receptacle, said latch handle being manually actuated for releasing the hinged cover, said upper hook member being adapted for engaging the lug member on said cover for releasably locking the cover in closed 75 position, said lower hook portion being adapted for engaging the retaining member on the rear face of the follower plate for retaining the same in retracted position and for automatically releasing the follower plate upon closing the said cover. 80
5. A dispenser for folded sheets, comprising a container for receiving a stack of sheets, said container comprising a bottom wall, side walls, a front wall and a rear wall, said side walls extending substantially to the horizontal medial plane of the dispenser, a cover hinged to said side walls, said cover being provided with leg portions integral therewith, said leg portions being pivoted at one end thereof to said side walls and extending within the receptacle, said cover terminating short of the upper edge of the front wall when in closed position thereby providing an elongated slot for withdrawal of the sheets. 85
6. A dispenser for folded sheets comprising a container for receiving a stack of sheets, said container comprising a bottom wall, side walls, a rear wall and a front wall, spaced ribs provided in the said bottom wall, said ribs being adapted to support the stack of sheets in spaced relation 90 above the said bottom wall, and a follower plate hinged to the rear wall and adapted to bear against the stack of sheets, said follower plate having a foot portion positioned between the ribs in the bottom wall of the receptacle and ex- 95

tending toward the front wall of the receptacle for guiding the follower plate and supporting the lower edge portions of the rearmost sheets in the stack, said cover terminating short of the 5 upper edge of the front wall when in closed position thereby providing an elongated slot for withdrawal of the sheets.

7. A dispenser for folded sheets, comprising a container for receiving a stack of sheets, said 10 container comprising a bottom wall, side walls, a rear wall and a front wall, spaced ribs provided in the said bottom wall, and a follower plate hinged to the rear wall adapted to bear against the 15 stack of sheets, said follower plate having an upper flange portion adapted for engaging the upper rear edge portion of the stack of sheets and a foot portion extending toward the front wall of the receptacle and guided by the spaced 20 ribs and positioned therebetween, said foot portion being adapted to support the lower edge 25 portions of the rearmost sheets in the stack, said cover terminating short of the upper edge of the front wall when in closed position thereby providing an elongated slot for withdrawal of the sheets.

8. A dispenser for folded sheets, comprising a container for receiving a stack of sheets, said 30 container comprising a bottom wall, side walls, a rear wall and a front wall, a cover hinged to said receptacle comprising a top wall, side walls and a front wall, wing portions integral with the rear wall and extending inwardly of the container for supporting and guiding the side walls of the hinged cover, the upper edge portion of the 35 front wall of said receptacle being bent outwardly of the container to provide a lip portion, the lower edge portion of the front wall of said hinged cover terminating short of the upper edge of the front wall when in closed position and being bent outwardly to provide a lip portion adjacent 40 said first lip portion and spaced therefrom to provide an elongated slot for withdrawal of the sheets.

9. A dispenser for folded sheets, comprising a

5 container for receiving a stack of sheets, said 10 container comprising rear, front, bottom and side walls, a cover hinged to said container, said cover terminating short of the upper edge of the front wall when in closed position thereby providing an 15 elongated slot for withdrawal of the sheets one at a time, a follower plate within the container 20 adapted to bear against the rear of the stack of sheets for urging the stack toward said slot, said follower plate being urged forwardly by spaced 25 link bars, one end of said link bars being pivoted to the rear wall of said container, the other end of said link bars being slotted for slidably receiving lug portions provided in the rear face of 30 said follower plate and curved to reduce the bearing surface of same against the follower plate, and means for yieldingly urging said link bars toward the said slot.

10. A dispenser for folded sheets, comprising a container for receiving a stack of sheets, said 20 container comprising rear, front, bottom and side walls, a cover hinged to said container, said cover terminating short of the upper edge of the front wall when in closed position thereby providing an 25 elongated slot for withdrawal of the sheets one 30 at a time, a follower plate within the container adapted to bear against the rear of the stack of sheets for urging the stack toward said slot, said follower plate being urged forwardly by spaced 35 link bars, one end of said link bars being pivoted to the rear wall of said container, the other end of said link bars being slotted for slidably receiving lug portions provided in the rear face of 40 said follower plate, the portions of each link bar above and below the slot being curved, said lower portion of each link bar being offset and out of alignment with the said upper portion, thereby reducing frictional contact of said forward end of the link bars against the follower plate, and means for yieldingly urging said link bars toward the said slot.

FRANK L. BROEREN.
ARCHIE S. KRUEGER.
